UNITED STATES PATENT OFFICE.

WERNER SCHMID, OF WHITE PLAINS, NEW YORK, ASSIGNOR TO AUDREY DREIFUSS, EMIL DREIFUSS, JEROME DREIFUSS, LOUIS DREIFUSS, AND SYBILLE DREIFUSS, COPARTNERS DOING BUSINESS AS NATIONAL LACE AND EMBROIDERY COMPANY, OF NEW YORK, N. Y.

DESIGN FOR EMBROIDERED TEXTILE FABRIC.

Application filed April 28, 1928. Serial No. 26,499. Term of patent 3½ years.

To all whom it may concern:

Be it known that I, WERNER SCHMID, a citizen of the United States, residing at Battle Hill, White Plains, county of Westchester, in the State of New York, have invented a new, original, and ornamental Design for Embroidered Textile Fabric, of which the following is a specification, reference being had to the accompanying drawing, forming a part thereof, in which the figure is a plan view of a piece of embroidered fabric embodying the design.

I claim—

The ornamental design for embroidered textile fabric, as shown.

This specification signed this 27th day of April A. D. 1928.

WERNER SCHMID.
